UNITED STATES PATENT OFFICE

129,363

DESIGN FOR A LIGHTING FIXTURE OR SIMILAR DEVICE

Henry K. Pracht, Irwin, Pa., assignor to Pittsburgh Reflector Company, Pittsburgh, Pa., a corporation of New Jersey

Application June 28, 1941, Serial No. 101,782

Term of patent 14 years

To all whom it may concern:

Be it known that I, Henry K. Pracht, a citizen of the United States, residing at Irwin, Pennsylvania, have invented a new, original, and ornamental Design for a Lighting Fixture or Similar Device, of which the following is a specification, reference being had to the accompanying drawing, forming part thereof.

In the drawing, the single figure is a perspective view of a lighting fixture or similar device embodying my new design.

The opposite end of the fixture disclosed in the drawing is substantially the same as the end shown.

I claim:

The ornamental design for a lighting fixture or similar device, substantially as shown and described.

HENRY K. PRACHT.
